UNITED STATES PATENT OFFICE.

BENJAMIN G. MILLER AND FLORENCE HAZEN MILLER, OF CRETE, NEBRASKA.

MUSIC-HOLDER.

1,299,374.

Specification of Letters Patent.

Patented Apr. 1, 1919.

Application filed April 27, 1918. Serial No. 231,198.

To all whom it may concern:

Be it known that we, BENJAMIN G. MILLER and FLORENCE HAZEN MILLER, citizens of the United States, residing at Crete, in the 5 county of Saline and State of Nebraska, have invented new and useful Improvements in Music-Holders, of which the following is a specification.

This invention relates to improvements in 10 music holders, specially adapted for use for holding sheet music on a piano or other instrument and to enable the sheet music to be readily turned, the object of the invention being to provide an improved device of the 15 character which is simple in construction and which is adjustable so that the same can be used for holding sheet music of various sizes.

With the above and other objects in view 20 the invention consists in the construction, combination and arrangement of devices hereinafter described and claimed.

In the accompanying drawings:—

Figure 1 is a front elevation of a sheet 25 music holder constructed and arranged in accordance with our invention.

Fig. 2 is a longitudinal sectional view of the same on the plane indicated by the line 2—2 of Fig. 1.

Fig. 3 is a front elevation of a modified 30 form of the invention.

Fig. 4 is a sectional view of the same on the plane indicated by the line 4—4 of Fig. 3.

Fig. 5 is a front elevation of another modified 35 form of the invention.

Fig. 6 is a longitudinal sectional view of the same.

The music holder comprises a pair of end 40 bars and also connecting bars. In the form of the invention shown in Figs. 1 and 2 the end bars are indicated at 1 and the connecting bars are indicated at 2. The end bars may be made of wood or other suitable material and are covered on their inner sides 45 and at the ends with felt 3 or other suitable cushioning material to prevent the holder from scratching the piano or other instrument on which it may be used.

Each connecting bar 2 is longitudinally 50 adjustable and comprises a bar of telescopically related tubular members 4, 5, which are attached at their out ends to the end bars.

Each member 5 is slidable in the member 4 55 and is provided with a plunger 6 which fits

in the bore of the member 4. Each member 4 has a cap 7 secured thereon and provided with a central opening through which the member 5 extends.

By the provision of the longitudinally adjustable connecting bars, the music holder is adapted to be used for holding sheet music of various sizes.

Spring fingers 8 are also provided which are secured on the end bars 1 and are adapted to bear on the sheet music and to hold the same open and on the connecting bars between the end bars. The clamping fingers are secured to the end bars by thumb screws 9 which also form pivots, so the clamping 65 fingers may be turned and so that the clamping fingers may be caused to bear on the sheet music at any desired point and thus avoid covering any of the staves. The pivots 9 also enable the clamping fingers to be 70 turned parallel with the ends and to bear thereon when it is desired to arrange the clamping fingers entirely out of the way.

In the form of the invention shown in 75 Figs. 3 and 4 the spring clamping fingers 8^a are pivotally secured by thumb screws 9^a on sleeves or loops 10 which sleeves or loops are 80 slidable on guide rods 11 which are secured, as at 12, on the end bars of the holder. This construction enables the spring clamping 85 fingers to be adjusted vertically on the end bars as well as to be turned in any desired direction.

In the form of the invention shown in 90 Figs. 5 and 6 the connecting bars 2^a are integral and non-adjustable. Sleeves 13 are 95 slidable longitudinally on the center connecting bar and the spring clamping fingers 14 are pivotally secured to the sleeves by thumb screws 15. Said thumb screws also serve to clamp the sleeves to the center cross bar in any desired adjustment, in accordance with the size of the sheet music to be used on the holder.

While we have herein shown a preferred 100 embodiment of our invention we would have it understood that changes may be made in the form, proportion and construction of the several parts, without departing from the spirit of our invention and within the scope 105 of the appended claim.

Having thus described our invention we claim:—

A music holder comprising a frame including bars, sleeves slidably engaged upon 110

said bars, and disposed at opposite sides of
said frame, a spring clamping finger asso-
ciated with each sleeve, and a thumb screw
extending through each finger and the asso-
ciated sleeve whereby said fingers will be
5 pivoted upon the sleeves, said thumb screws
being engageable with the bars whereby said

sleeves may be secured in adjusted positions
upon said bars.

In testimony whereof we affix our signa- 10
tures.

BENJAMIN G. MILLER.
FLORENCE HAZEN MILLER.
